SEAL FOR ROTARY DRUM DRIER

Ronal H. Whyte, Dayton, and Nelson J. Pansing, Brookville, Ohio, assignors to General Motors Corporation, Detroit, Mich., a corporation of Delaware

Application February 8, 1957, Serial No. 639,100

7 Claims. (Cl. 34—133)

This invention relates to a domestic appliance and more particularly to a clothes dryer of the axial air flow type.

The present invention contemplates providing a clothes dryer wherein the drying air passes axially through a horizontally arranged tumbling drum and wherein the air is exhausted from the drum through the front access opening of the drum. The air leaving the access opening passes into a second exhaust opening that is vertically spaced from the access opening, the door of the dryer directing the air into the second exhaust opening.

It is an object of this invention to provide a dryer of the type described above wherein air is exhausted from the tumbling drum of the dryer adjacent the door of the dryer and where means are provided for preventing clothes from plugging the discharge air flow path of the dryer.

A more specific object is to provide a clothes dryer of the type wherein air is discharged adjacent the door of the dryer and wherein a perforated clothes deflecting baffle is secured to the door for preventing clothes from piling up adjacent the door and plugging the discharge air flow path of the dryer.

Another object is to provide a clothes dryer of the type having a vertically extending bulkhead and wherein a heater box is secured to the bulkhead, the heater box supporting an electric heating element and having an air inlet and an air outlet located in alignment with the rear perforated wall of the tumbling drum of the dryer.

Still another object is to provide a dryer of the type having a tumbling drum formed with a rear perforated wall portion located adjacent a vertically extending bulkhead, and having a perforated seal circumscribing the rear perforated wall portion of the tumbling drum and interposed between the bulkhead and tumbling drum to form an inlet air chamber for the tumbling drum, the seal being effectively cooled by air passing through the perforations formed in the seal.

Further objects and advantages of the present invention will be apparent from the following description, reference being had to the accompanying drawings, wherein a preferred form of the present invention is clearly shown.

In the drawings:

Figure 1 is a vertical sectional view of the clothes dryer of this invention;

Figure 2 is a fragmentary front view of the door assembly of the dryer showing the perforated clothes deflecting baffle of this invention;

Figure 3 is a sectional view taken along line 3—3 of Figure 1;

Figure 4 is a plan view of the perforated seal shown in Figure 3; and

Figure 5 is a front elevational view partially in section of the drier shown in Figure 1.

Referring now to the drawings and more particularly to Figure 1 a drier generally denoted by reference numeral 10 is provided with an outer cabinet including a top wall 12, a front wall 14 and a rear wall 16. A vertically extending bulkhead 18 is welded or otherwise secured to the dryer cabinet. A tumbling drum 20 is located within the dryer cabinet and is supported for rotation by a bearing 22 that is fixed to the bulkhead 18.

2

The tumbling drum has a rear perforated wall portion 24 and is provided with a front access opening 26. The rear perforated wall portion 24 of the tumbling drum is circumscribed by a felt seal 28 that is fixed to a flanged member 30 by a clamping ring 32. The seal 28 abuts the rear wall of the tumbling drum 20 and forms an inlet air chamber with the vertically extending bulkhead 18. A heater box assembly generally denoted by reference numeral 34 is secured to the bulkhead 18. The heater box includes a heater housing 36 having side walls 38 one of which is shown in the sectional view of Figure 1. The heater box assembly further includes a shield member 40 and a heat reflector member 42 spaced from the shield member 40 by spaced bearings 41. The shield member 40 is provided with an opening 44 that fits within openings formed in the bulkhead 18 and in the reflector member 42 and these openings provide an air discharge outlet for the heater box assembly 34. An electric heating element 46 is mounted between the housing 36 and the heater shield 40. The housing assembly 36 is provided with an air inlet passage 48 at the top thereof. The housing 36, shield 40 and heat reflector 42 are secured to the bulkhead 18 by screws as shown in Figure 1.

The front end of the clothes dryer is provided with a port plate generally denoted by reference numeral 50 that includes a peripheral wall portion 52 forming an access opening that is in alignment with the access opening 26 of the tumbling drum. A felt seal 51 is interposed between the port plate 50 and the flanged portion 53 of the tumbling drum. Suitable bearing members 57 are also interposed between the port plate 50 and flanged portion 53 which supports the forward end of drum 20 during its rotation. These bearing members preferably are secured to the outer side of peripheral wall portion 52 and may be made of nylon or any other suitable material. The port plate 50 carries a seal 54 and has an air discharge opening 56 vertically spaced from the opening formed by peripheral wall 52. The port plate 50 is preferably bolted to the front cabinet wall 14 by fasteners (not shown). The exhaust opening 56 formed in port plate 50 is in alignment with a discharge passage 58 that communicates with a vertically extending duct 60 located immediately below the port plate 50. The vertically extending duct 60 may be welded or otherwise secured to an air box 62. A door 64 is pivotally secured to the front wall 14 of the dryer and has an inner recessed portion 66 that operates to direct air flowing axially through the tumbling drum into the vertically extending duct 60.

The air box 62 is provided with an opening 68 that communicates with the vertically extending duct 60. A lint filter element 70 is located within the air box 62 in the path of air moving downwardly through duct 60. The air box 62 is open at 72 and the interior of the air box is connected with a blower 73 by means of a duct 76. The blower includes a housing 74 and an impeller 78 that is driven by an electric motor 80. The electric motor also drives the tumbling drum through belts 82 and 84 and through pulleys 86, 88, 90 and 92. The blower housing 74 is provided with an outlet 94 that is connected with suitable duct work (not shown) that leads to the exterior of the cabinet.

With the above described arrangement air is constantly exhausted from the interior of the tumbling drum by the blower 73. The air leaving the tumbling drum passes through the peripheral wall portion 52 of the port plate 50, thence through the recessed portion 66 of the door 64, through air passages 56 and 58, downwardly through duct 60, through air box 62, through duct 76 and then into the blower where the air is discharged through out-

let 94 to the atmosphere. Make up air for the dryer is supplied through an air passage 96 formed in the rear wall 16 of the dryer. This air passes downwardly through passage 48 into the heater box 34 where the air is heated by heating element 46. The air leaves the heater box through outlet passage 44 and then passes through the rear perforated wall portion 24 of the tumbling drum into the interior of the tumbling drum.

The door 64 of the dryer is provided with a perforated baffle 98 that operates to deflect clothes away from the recessed portion 66 of door 64, but which permits the passage of air therethrough. The baffle thus insures that clothes will not find their way into the recessed portion 66, and thus positively prevents plugging of the discharge air flow path from the tumbling drum 20. The baffle 98 is secured to the inner face of door 64 by bolting or otherwise securing the baffle thereto.

It should be noted that the felt seal 28 is protected from heat radiating from heating element 46 by the heat reflector element 42, which is preferably formed of an aluminum clad steel. The reflector 42 being spaced from heater shield 40 by bumps 41, provides an air space between the reflector 42 and the shield 40 which operates to protect the seal 28 from heat being transferred from the heating element 46. The reflector 42 thus adds an additional layer of material between heating element 46 and seal 28 and by its location also provides an air space therebetween.

Additional means are also provided for maintaining the seal 28 within safe temperature limits. To this end the seal 28 is provided with a plurality of metal eyelets 100 that provide air passages therethrough. With the arrangement air is constantly pulled through the eyelets 100 to cool the felt seal when the dryer is operated due to the fact that the tumbling drum is constantly being exhausted by blower 73. With the arrangement just described the felt seal 28 is cooled and is kept at a temperature below the disintegrating temperature of the seal material.

While the form of embodiment of the invention as herein disclosed constitutes a preferred form, it is to be understood that other forms might be adopted, as may come within the scope of the claims which follow.

What is claimed is as follows:

1. A clothes dryer comprising, an outer casing having an opening, a peripheral wall supported within the casing opening and defining an access opening, a door pivoted to said casing opening and closing said access opening and having a portion spaced from said peripheral wall to form an air passage when in the closed position but otherwise engaging said wall to seal the opening, a tumbling drum in said casing having a loading opening in alignment with said access opening, means for supplying heated air to said drum and for exhausting said air from said drum at the space between said peripheral wall and said door, and a perforated baffle fixed to said door and extending angularly over said space when the door is closed whereby clothes in said tumbling drum are prevented from entering said space and are urged toward said tumbling drum.

2. A clothes dryer comprising, a casing having a front access opening closable by a door pivoted to said casing, a vertically extending rear bulkhead in said casing, a cylindrically shaped tumbling drum supported for rotary movement within said casing and having a front loading opening located in alignment with said access opening, said tumbling drum having a rear perforated wall portion located adjacent said bulkhead, a heater box fixed to said rear bulkhead having an air inlet in communication with the exterior of said casing and having an outlet in communication with the rear perforated wall portion of said drum, and a seal member fixed to said rear bulkhead having a portion abutting the rear wall of said tumbling drum, said seal member circumscribing the rear perforated wall portion of said tumbling drum and being formed with

4 a plurality of radially extending passages whereby air passing through said passages cools said seal.

3. A clothes dryer comprising, an outer casing, an access opening in one wall of said casing defined by a peripheral wall, a door pivoted to said casing opening and closing said access opening and having a portion spaced from said peripheral wall when in the closed position but otherwise engaging said wall to seal the opening, a tumbling drum in said casing having a loading opening in alignment with said access opening and having a rear perforated wall portion, a pivotally extending bulkhead located adjacent the rear wall of said drum, a heater box associated with said bulkhead having an air inlet communicating with the exterior of said casing and having an air outlet located adjacent the rear perforated portion of said drum, a heater element in said heater box for heating air passing through said box, a cylindrically shaped felt seal having a plurality of radially extending passages fixed to said bulkhead and engaging the rear wall of said tumbling drum, said seal circumscribing the perforated portion of said tumbling drum rear wall, means for exhausting air from said drum at the space between said peripheral wall and said door, and a perforated baffle fixed to said door and extending over said space when the door is closed whereby clothes in said tumbling drum are prevented from entering said space.

4. The structure defined in claim 2 wherein said seal member comprises a cylindrically shaped felt member having a plurality of hollow metal eyelets extending radially therethrough and forming radially extending air passages.

5. A cylindrically shaped seal ring adapted for interposition between a rotary tumbling drum and a fixed part of a clothes dryer for forming an air chamber therebetween formed of a flexible material and having a plurality of radially extending passages facilitating air flow therethrough.

6. A cylindrically shaped seal ring adapted for interposition between a rotary tumbling drum and a fixed part of a clothes dryer for forming an air chamber therebetween formed of a felt material and having a plurality of radially extending passages defined by hollow metal eyelets in said felt material.

7. A clothes dryer comprising, an outer casing having a vertically extending front wall, a tumbling drum having a rear perforated wall portion mounted for rotation in said casing and having a front loading opening facing said front wall, heating means having an inlet communicating with the exterior of said casing and having an outlet communicating with said rear perforated wall, an access opening in said front wall defined by a peripheral wall in alignment with said loading opening, a door covering said access opening having a depressed portion spaced from said peripheral wall at the bottom of said door and defining an exhaust air space, a duct connected to said air space below said opening, a blower having a suction inlet connected with said duct for drawing air past said heating means, axially through said drum, and through said exhaust air space, and a substantially semi-circular perforated baffle having an upper side fixed to said door and a lower side depending angularly over said exhaust air space, said baffle permitting free flow of air therethrough and urging the clothes toward said drum while preventing clothes from entering and blocking said exhaust air space.
